UNITED STATES PATENT OFFICE.

FRANK T. WERNIMONT, OF MONTICELLO, IOWA, ASSIGNOR TO HALL MANUFACTURING CO., OF MONTICELLO, IOWA.

WIRE-FENCE CLAMP.

1,122,829.

Specification of Letters Patent.

Patented Dec. 29, 1914.

Application filed October 28, 1912. Serial No. 728,233.

To all whom it may concern:

Be it known that I, FRANK T. WERNIMONT, a citizen of the United States, and a resident of Monticello, in the county of Jones and State of Iowa, have invented a new and useful Wire-Fence Clamp, of which the following is a specification.

My invention relates to means whereby a portion of a woven (or other) wire fence 10 may be clamped and held while stretching it taut, and, if desired, after its securement to a post.

The principal object of the invention is to provide a more simple device of this character than has been heretofore produced, which will firmly clamp and securely hold the fence from slipping or sagging.

Another object is to provide a novel combination of elements of simple character, the 20 binding one of which may be almost instantly engaged with or disengaged from the other members. And in this connection it is an object to provide a device of such construction that a very slight loosening of 25 the retaining nuts (without their removal) will permit said binding element to be disengaged therefrom, whereupon the fence may be instantly removed, even though the securing bolts pass through the meshes 30 thereof.

It is an object to provide a device of great simplicity which is more facile and efficient in its operation, and more economical in construction and therefore to the purchaser, 35 than clamps of similar nature heretofore produced.

It is an object to provide a device of the character described, a part of which only 40 may be attached to fence posts, buildings such as barns, poultry houses, etc., whereby a portable inclosure may be readily constructed.

It is an object to provide novel combined means whereby the binding elements may be 45 drawn very tightly together.

The invention accordingly consists in structural details, and in the arrangement, relationship and combinations of the parts hereinafter described and shown in the accompanying drawings, in which:

Figure 1 is a perspective view of my improved clamp, a portion thereof broken away to show the placement of the fence wire; Fig. 2, a top plan; Fig. 3, a longitudinal, central section; Fig. 4, a front eleva-

tion, the binding element removed; Fig. 5, a perspective detail of one of the locking-bolts; and Fig. 6, an end view, the parts shown in one of the operations of assembling.

80

Coming now to a detailed description of said drawings, in which the same numeral uniformly designates the same part, 2 indicates a wood section which for convenience sake I shall herein term a standard and which may be of any preferred cross section and may, in some of the applications of my improvements, constitute one of the posts. It is provided with transversely arranged apertures 3.

70

4 designates a binding element—a clamping rib, approximately an oblong rectangle in its cross section and provided with countersunk apertures 4^a for the reception and passage of wood-screws 5, the threads of 75 which engage the standards 2 to hold it securely thereto, and the heads of which seat in the countersinks to provide a flush face. The rib is provided also with apertures 9 for the reception of locking or securing-bolts, 6, each of which has preferably a half-round head 7, a threaded shank 8 adapted to pass through the aperture 9, an angular and preferably square neck 10, greater in its cross sectional area than the area of the shank 85 8, and an unthreaded circular portion 11 intermediate the portions 8 and 10.

80

12 indicates a binding element comprising a base or body portion 13, having flanges 14 providing a channel 15 in which the rib 90 4 preferably wholly lies. Its base is provided with slots 16 of very little greater width than the neck 10 of the bolt, whereby it may slide therein but is locked thereby from turning, and said slot terminates 95 at its lower end in an enlarged opening 17 of sufficient width to permit the passage of the bolt head therethrough.

18 designates a fragment of woven-wire fence; and 19 a nut, both of ordinary construction.

90

The operation and uses are as follows: The rib 4 is first secured to the post or standard 2 by the screws 5. The shanks of the bolts 6 are then slipped through the 105 apertures 9 and 3, and the nut 19 threaded loosely on said shank. The fence section is then positioned. The parts above described will thus occupy the relative positions shown in Fig. 6, with the fence-wire 110

meshes straddling the smooth circular portion 11 of the bolt. The binder 12 is then positioned with the enlarged openings 17 over the heads 7 and pressed firmly down 5 to bend the wires to conform to the similar shapes of the opposed faces of the binding elements 4 and 12, whereupon the latter is slipped downwardly to cause the square stem 10 to enter the slots 17, the bolt head 10 being restrained by the material at the sides of the slots. The nuts 19 are then drawn taut, and this may be done with great effectiveness by reason of the square stems 10 being prevented by the slot-walls from 15 turning.

The rib 4 being of such size that it lies wholly within the channel 15, the flanges 14 are, in and by the act of turning the nuts very taut, drawn with great force down 20 against the wires to compress them against and, if sufficient force be used, slightly into the yielding wood of the standard 2, whereby said wires are held in three effective ways, to-wit: by the opposed faces of the 25 opposed binding elements 2 and 12; by being bent and bound by the corners thereof; and by the compression exerted on them by the flanges 14 which, it will be observed, are oppositely flared or directed and thus adapted 30 to resist draft on the wire from either direction.

To remove the wire it is necessary only to slightly loosen the nuts 19, whereupon the binder 5 may be removed by sliding it upwardly until the bolt heads coincide with the apertures 17 and then slipping it thereover, whereupon the other elements may be slipped from off the wires, or vice versa. 35

Because of its extreme simplicity, and of 40 the facility and rapidity with which it may be manipulated, the invention will be of great utility in portable fences, for the ribs may be removably secured (as shown) by the screws 5 to posts, or the standards themselves 45 may be used as posts, and the wire quickly detached from the fixed posts (if such be used) and moved from place to place. Again, the ribs 4 may be secured to corners and sides of buildings such as 50 poultry houses, stables, animal pens and the

like, and a confining inclosure readily constructed by the mere placement of two outer posts or two standards 2 equipped with the principal parts of my improvement. A construction of this character may be readily moved about as desired. 55

It will be noted that there are no frail elements, no useless ones which entail added expense to the purchaser, no projecting portions which might injure the person or 60 clothing of the operator or which might be loosened by stock rubbing thereagainst when the device is used as a fence part, and that the operations of assembling and disassembling and the ultimate result are 65 achieved in a more facile, efficient and economical manner than heretofore.

Having thus set forth the construction and operation, the purposes and advantages of my invention, I claim as new and desire 70 to secure by Letters Patent the following, to-wit:—

A fence clamp including a standard, a rib of greater width than thickness removably secured upon the standard, bolts passed 75 through the rib and standard and having their headed terminals projecting beyond the outer surface of the rib, and a U-shaped binding element having an outer face of materially greater width than the similar 80 dimension of the rib and arranged in parallelism to the outer face of the rib, the side edges of the element being at right angles to the face, the hollow portion of said 85 element being equal in depth to the thickness of the rib with the side walls of said hollow portions disposed at an angle to the forward face thereof, said binding element being formed with key-hole slots to cooperate with the bolts, and means for drawing 90 the bolts through the rib and standard to force the binding element toward the rib. 95

In witness whereof I hereunto sign my name in presence of two subscribing witnesses.

FRANK T. WERNIMONT.
